PROCESS FOR CONVERSION OF HEAVY HYDROCARBON OILS

William F. Arey, Jr., and Robert J. Fritz, Baton Rouge, La., assignors to Esso Research and Engineering Company, a corporation of Delaware

Application August 17, 1953, Serial No. 374,598

5 Claims. (Cl. 208—54)

The present invention relates to an improved process for conversion of heavy hydrocarbon oils. More particularly, the invention relates to a process for obtaining from heavy residual oils products, particularly gas oil, of high quality and low contaminant content by a thermal non-catalytic conversion process. In another aspect, the invention relates to a multiple phase fluidized solids coking system which is thermal and non-catalytic for producing high quality catalytic cracking feed stock from heavy residua which are high in catalyst contaminants and other undesirable ingredients.

In the prior art, it has been suggested that topped crudes and other viscous hydrocarbon oils, particularly residua of low API gravity, may be converted by essentially non-catalytic thermal treatment to produce moderate quantities of lower boiling materials. The conventional process is accompanied by some production of the lighter gases such as hydrogen, methane, ethane, etc., and by degradation of a part of the feed to coke. Usually a small amount of low boiling products of the motor fuel boiling range are produced but these are of relatively low octane number. The most desirable product, and the one usually most sought in coking or other thermal processes applied to heavy residua, is a middle distillate such as a gas oil which can be largely converted by modern efficient catalytic cracking processes to motor fuels of high quality.

Unfortunately, many heavy residua contain relatively large proportions of undesirable materials which tend normally to be carried over into the heavy ends of the gas oil fraction. These materials include certain nickel and vanadium compounds, apparently of organic nature, which are potent poisons to the usual cracking catalysts. They include also certain materials which promote high Conradson carbon in the gas oil products, which is undesirable. Various attempts have been made in the past to keep these objectionable materials in the residue, to deposit them upon solid carriers such as coke produced in the conversion process, to catch them in "guard" beds of solids, to destroy them by burning, etc., without great success. At least some of the catalyst contaminants, for example, appear to volatilize with the gas oil, and to remain in this fraction upon subsequent fractionation. Even when present in the gas oil in only small concentrations, they are highly objectionable. Besides injuring or inactivating the catalyst in subsequent cracking, they tend to promote a high production of gas, especially hydrogen, in all conversion operations where they are present. Frequently they are potent dehydrogenation catalysts, thereby promoting both high gas production and high degradation of the feed to coke and coke precursors in catalytic conversions. They tend to accumulate in the heavier ends of conventional gas oils.

In the production of a 430 to 1050° F. gas oil from reduced crudes by thermal non-catalytic conversion or coking it is found to be extremely difficult to obtain a sharp cut-off or end point in the boiling range. It is quite impossible in commercial scale fractionation to

2

avoid inclusion of some small amounts of materials which, per se, have a boiling range up to 1100° F. or higher. These higher boiling components appear to include a relatively high proportion of the objectionable contaminant materials mentioned above. If the fractionation temperature range is lowered so as to avoid completely the carrying over of minor quantities of constituents of boiling range above 1050° F., including the objectionable contaminants, it must be brought down to around 900° F. or so. This results in greatly reduced production of gas oil. The use of steam or other distillation or stripping aids greatly aggravates the carry over of the objectionable metallic (or metallo-organic) components and the asphaltenes or coke precursors which usually are materials of high Conradson carbon number.

The objectionable character of the high boiling end components of the gas oil may be understood more clearly by data obtained in careful test distillations, at different end points, of gas oil obtained from an Elk Creek based (Wyoming) crude residuum. These data show the distribution of the most common and potent contaminants, nickel and vanadium (as oxides), in various fractions:

25

Table I

Type of Distillation	Equivalent Cut Point of Gas Oil, °F.	Wt. percent on 430° F. +	Contaminants, PTB ¹

¹ Pounds per 1,000 barrels.

It will be noted that the metallic content increases very rapidly in the heavier ends. Obviously, it is desirable to exclude, as far as practicable, the metallic constituents in the gas oil which goes to the catalytic cracker. It is desirable to do this without substantially reducing the volume of gas oil obtained from the residuum. The present invention affords a practical process and system for accomplishing this. This is achieved, in the present case, by coking the residual feed in a plurality of fluidized bed treatments at carefully selected and controlled conditions.

In conventional thermal coking, using the fluid solids technique, a mass of particulate solids, such as coke particles of the range of about 40 to 400 microns average diameter, is preheated to a temperature usually between about 1100° and 1400° F., or more, and then brought to a reaction or coking zone. Here the hot coke particles are contacted by the feed which is usually preheated though usually not substantially precracked or converted.

The reaction or coking temperature range in conventional systems is commonly about 950° to 1100° or 1150° F. The residual oil feed is vaporized and cracked by the sensible heat of the particles. The cracked and vaporized products then pass on to a fractionation stage where various products such as gas, gasoline, gas oil and a final residue are obtained. Apparently, as noted above, the objectionable metallic contaminants and the asphaltene and other constituents of high Conradson carbon member, i.e. coke precursors, etc., also are vaporized within this temperature range. As noted above, these are present in comparatively large proportions in the heavy ends of the gas oil.

According to the present invention, the first thermal coking or conversion stage is operated at or about conventional coking conditions of temperature, feed rate,

etc., so that the objectionable constituents mentioned may be intentionally volatilized and carried over. The heavy residual oil feed is introduced into a fluidized bed of hot particulate solids at the rate of about 1 pound per 5 to 50 pounds of solids per unit of time. The coking products are then passed directly from the first bed into and through a second fluidized solids bed stage which is operated for coking or conversion at a controlled temperature which is 100° to 300° F. lower than the temperature in the first bed. This lower temperature is so limited and controlled that the objectionable constituents which usually boil just above the gas oil end point are condensed and remain deposited, to a substantial degree, upon the solids of the bed. It has been found that this can be accomplished, according to the present invention, without substantial reduction in gas oil production. The overall quality of the gas oil as regards contaminants is very definitely improved. The lighter gas oil components pass through the bed quickly and are not substantially affected by it while the heavier components are partly condensed.

In effect, the less desirable heavy components of the gas oil stay in a coking reaction zone longer, though at lower temperature for the latter part of their stay, than in prior processes. As a result they are converted to a substantial degree to more volatile components, including lighter gas oil, and are separated quite effectively from their metallic constituents. Organic radicals associated with the metallic constituents appear to be cracked or otherwise converted, so that the metallic constituents tend to revert to inorganic ash and to remain with the solids of the bed. The coke promoters such as asphaltenes and other constituents responsible for high Conradson carbon in the usual gas oil products from coking likewise appear to be reduced in quantity.

Whatever the actual mechanism may be, it appears that the tempering and prolonging of reaction in the cooler bed is highly beneficial. Moreover, it appears that the prompt quenching of the products from the first bed, either before or while they pass through the subsequent cooler bed or beds, is highly beneficial. A series of three or more beds may be used, if desired, but ordinarily two are sufficient with the latter operating at a temperature of 50 to 300° F. or more, preferably 100° to 200° F., below that of the first bed.

It is recognized that the prior art has suggested the use of plural fluidized solids beds in sequential arrangement for various purposes. For example, in Jahnig patent, No. 2,420,542, flue gases from a regenerator are passed through a cooling bed of fluidized solids. The present invention, however, is applied to the much different problem of coking heavy or residual oils and it helps to solve the serious problem of carrying over cracking catalyst contaminants in the gas oil.

A preferred temperature range for the second bed is between about 750 and 950° F., particularly between 800 and 900° F. as compared with about 950 to 1100° F. for the first bed. The products from the first bed are preferably cooled in the second bed itself, although some cooling which may take place as they travel from the first bed to the second is also contemplated in the invention. Two separate modifications are shown in the drawings which are attached. It will be understood that these are exemplary only.

Referring now to the drawing, Fig. 1 shows in diagrammatical elevation one form of a system or process for converting heavy oils, such as crude residua wherein products from the first fluidized solids bed are passed through a second and cooler bed. Here they are cooled and further processed. The second bed itself is cooled by extraneous means, such as a cooling coil inserted therein. Fig. 2 shows a modification wherein the solids from a first bed are cooled by heat exchange before passing into the second bed. Fig. 3 shows still another

arrangement where solids from the second bed are circulated through a heat exchanger.

Referring now in detail to the drawings, in Fig. 1 a reactor vessel 11 of suitable type and construction is shown in which a lower or first bed 13 of fluidized solids may be supported and maintained. A stream of pre-heated solids such as coke particles from a burner (not shown) is brought into the first bed at a temperature in the general range of about 1100° to 1400° F. The incoming stream of solid particles is fed into the bed 13 through a line 15. Suitable fluidizing gas such as steam may be supplied through one or more lines 17 and the oil feed, preferably preheated, may be fed in through one or more nozzles 19 and sprayed into the beds. The vaporized oil cooperates with the steam to fluidize the bed 13.

A substantial part of the solids in bed 13 pass upwardly by elutriation into the bed 16 above a partition or grid 31, before they return and enter a stripping zone 21 defined by a partition 23 as described below. A stripping gas may be supplied to this zone 21 through one or more lines 25, as is well known in the art. From bed 13, the spent solids may be drawn off through a standpipe 27 under control of a valve 29 or equivalent. From here they are returned to a heater or burner, not shown, for reheating, though some of them may be withdrawn as product coke.

The upflowing velocity of the steam and/or other fluidizing gas within bed 13 is sufficiently high that at least some of the solid particles are constantly entrained upwardly out of bed 13 and through a perforate partition or grid 31 which extends transversely across the vessel 11. The gasiform stream, comprising the original fluidizing medium plus products of the coking operation in the lower bed carries the particles entrained from the lower bed up through the perforations and forms a second fluidized solids bed 33 upon the partition 31.

Bed 33 is cooled to a temperature of the lower range described above, i.e. 750 to 950° F., preferably 800 to 900° F. This is accomplished in Fig. 1 by inserting a cooling coil 35 in the bed and circulating a coolant through the coil. Heat exchange between a fluidized solids bed and a coil immersed therein is very efficient. An overflow conduit 37 controls the depth of the bed 33 and extends below the transverse perforate partition 31 and below the surface of bed 13, so as to seal against countercurrent gas flow from the lower bed. Fluidized solids in bed 33 flow down through conduit 37 and the lower bed overflows a partition 20 which defines the stripping zone 21 as previously mentioned.

Through the upper bed, the gaseous and vaporous products which boil below its temperature pass rapidly upward and out through a gas-solids separator such as cyclone 41 which is of conventional type with a dipleg 43 which returns solid particles, separated from entrainment in the products, to bed 33. The heavier vapors are condensed and remain for a relatively long time in bed 33. Eventually they are largely converted and the hydrocarbon products, now relatively free from contaminants, pass through cyclone 41 and out through line 45 to suitable recovery equipment, not shown.

Fig. 2 shows a somewhat different arrangement wherein in a vessel 51 is adapted to support a lower fluidized bed 53 and an upper fluidized bed 55. The particular means for fluidizing the lower bed are not part of the invention and may be of any known type. Hot solid particles are brought into the bed from a suitable preheater or burner, not shown, through a line 57. The oil feed, suitably preheated by means not shown, is brought in through any suitable means, preferably comprising a plurality of nozzles 59, being distributed so as not to cause bogging or serious agglomeration in the bed.

Coking and thermal cracking as well as vaporization takes place in bed 53, the cracked and volatilized prod-

ucts passing upwardly through a perforate partition 61. In this case, however, as distinguished from Fig. 1, although some small quantity of solid particles will be carried up through the perforations in 61, the major proportion of solids is first taken downwardly from a stripping zone 63, defined by a partition 65, the upper edge of which forms an overflow wier. The overflowing solids pass down through the stripping zone 63, counter-current to a suitable upflowing stripping gas, supplied from any suitable source. From here they, or a suitable portion of them, pass through a standpipe 65, control valve 67, and U-bend 69, into a heat exchanger 71. Here they are cooled to the desired temperature, and then passed on up into the second bed 55 through a line 73. Suitable aerating and fluidizing gases may be introduced at suitable points to cause the solids to flow as described. The heat exchanger may be utilized to help preheat spent solids from the upper bed, to produce steam, etc.

The solids in the upper bed 55 flow over the upper inlet end of a conduit 75 which extends down through the partition or grid 61 into the lower bed 53. A branch line 76 is provided to take the cooled solids out of the second bed 55 and return them to the burner. This line also branches into a third line 77 through which the solids from the second bed can be returned directly to heat exchanger 71. This latter arrangement reduces the load on heat exchanger 71 somewhat and results in higher thermal efficiency. Appropriate valves 78, 79 and 80 are provided for control. The spent solids which are returned to bed 53 down through stripper 63 and into line 69 or to line 81 and valve 82 back to a heater or burner, or part of the product coke may be withdrawn as such and only part burned and reheated.

The products from the second and cooler coking bed pass overhead through cyclone 83 which returns the separator solids to the bed through a dipleg 84. The solids-free gases and vapors then pass on through a line 85 to fractionation and other recovery equipment.

In Fig. 3 still another arrangement is shown wherein cooling of the solids in the second bed is accomplished by circulating them from the second bed through a heat exchanger and back to the same bed. A reactor vessel 101 contains a lower fluidized bed 103 to which hot solids, preferably coke particles, are fed from a heater or burner through a line 105. Fluidizing gas, usually steam, though gaseous hydrocarbons or hydrogen or nitrogen may be used, is introduced through one or more inlets 107. Three are shown. Bed 103 reaches a level where it overflows a partition 109, which defines a stripping zone 111. A stripping gas such as steam is introduced through a line 113 to strip occluded gases from the descending solids which pass out through line 115 to a burner or to a product coke receiver.

Fluidizing is sufficiently active that some coke particles are carried up with the product vapors through a perforate partition or grid 117 on which a second fluidized bed 119 is formed. This bed reaches a level predetermined in part by a partition 121 over which part of the coke may flow to return to the lower bed. Partition 121 extends into the lower bed so as to prevent products from the lower bed from by-passing the upper bed.

In addition to the partition 121, a conduit 123 leads out of vessel 101 at approximately the same level, or slightly lower, so that a substantial stream of the fluidized solids may flow through a heat exchanger 125. This exchanger is cooled by any suitable means, e.g. it may be used to generate steam for the coking and associated operations. The cooled solids, after passing through heat exchanger 125, are returned to bed 119 through a line 127, with the assistance of a lifting or aerating gas introduced through one or more lines 129.

By the means just described, the temperature of the second bed may be accurately controlled so as to control the separation of contaminants from the products. The products flow out through a cyclone 131, having a solids return line 133, into a product line 135.

It will be understood that various modifications not shown may also be used within the spirit of the invention. For example, the systems of Figs. 1 and 2 may be combined in respect to the use of both a heat exchanger outside and a cooling coil inside the upper bed. Since the quantities of heat involved are quite large, such a combination may be needed for proper control in large units. Other changes and modifications such as will suggest themselves to those skilled in the art may also be made.

What is claimed is:

1. The process of converting residual hydrocarbon oil of relatively high metallic cracking catalyst contaminant content to gas oils of relatively low content of said contaminants which comprises feeding a stream of solid coke particles within the 40 to 400 micron average diameter range, preheated to a temperature of at least 1100° F., into a conversion zone at a controlled rate, passing a gasiform stream upwardly through said solids at a rate sufficient to cause said solids to form a fluidized solids bed overhead, feeding said oil into said bed at a rate of $\frac{1}{2}$ to $\frac{1}{10}$ the rate, on a weight basis per unit of time, of said controlled rate of feeding solids, contacting said oil with said solids in said bed at a temperature of about 950° to 1150° F. for a sufficient time to convert a substantial proportion of the oil to gas oil vapors, removing coke particles from said first bed and forming a substantially cooler second fluidized bed of said solids superposed above said first-mentioned fluidized solids bed in said conversion zone and supported on a perforated partition, and contacting said vapors with said second bed at a temperature of about 750° to 950° F. for a sufficient time to condense and to substantially further convert a portion thereof to give additional desirable oil vapors, thereby removing some of said metallic constituents.
2. Process according to claim 1 wherein the second bed is cooled 50 to 300° F. below the temperature of the first bed.
3. Process according to claim 1 wherein the second bed is cooled by means of a cooling coil inserted therein.
4. Process according to claim 1 wherein coke particles are recirculated from the second bed through a heat exchanger to cool said second bed.
5. Process as in claim 1 wherein coke solids from the first bed are withdrawn from the first bed, cooled by heat exchanger, and reintroduced to form said second bed.
